United States Patent Office

Des. 180,540
Patented June 25, 1957

180,540

CIGARETTE

Robert L. Weber, III, West Hartford, Conn.
Application April 2, 1956, Serial No. 40,876

Term of patent 14 years

(Cl. D85—6)

FIG. 1

FIG. 2

FIG. 3

Fig. 1 is a perspective view of a cigarette showing my new design;

Fig. 2 is a similar view looking at the cigarette from the opposite direction;

Fig. 3 is a plan view of the cigarette wrapper disposed in a single plane.

I claim:
The ornamental design for a cigarette, as shown.
